UNITED STATES PATENT OFFICE.

JOHN J. HAZLEWOOD, OF PITTSBURGH, PENNSYLVANIA.

TRANSFER APPARATUS.

Application filed October 1, 1921. Serial No. 504,820.

To all whom it may concern:

Be it known that I, JOHN J. HAZLEWOOD, a citizen of the United States, residing at Pittsburgh, in the county of Allegheny and State of Pennsylvania, have invented certain new and useful Improvements in Transfer Apparatus; and I do hereby declare the following to be a full, clear, and exact description of the invention, such as will enable others skilled in the art to which it appertains to make and use the same.

This invention relates to transfer apparatus of general application.

An aim is to provide a construction which is an improvement on, simpler and more efficient than that set forth in Letters Patent of United States #1,398,188 issued to me on November 21, 1921.

The invention resides in the construction attaining the various novel functions, combinations and advantages which are herein-after set forth relative to accompanying drawings of one practical embodiment.

In said drawings:

25 Figure 1 is a plan view of the improved apparatus.

Figure 2 is a view of the apparatus, partly in side elevation, and partly in vertical section, and

30 Figure 3 is a rear elevation of the apparatus.

Referring specifically to the drawings, wherein like reference characters designate like or similar parts, the invention will be described by way of example, in connection with rolls A, which are rotatably mounted, and adapted to have material passing therethrough transferred therefrom. The invention of course is not limited to such use, but on the other hand is of general application, and may be used for instance not only in connection with rolling mills, but in ship yards in connection with railroads, the removal of wreckage, and otherwise.

45 On a suitable foundation 4, the track rails 5 may be laid for the travel of suitable rolling stock thereon. This rolling stock may consist of a plurality of substantially rectangular skeleton frames 6 to the ends of which, as by means of bolts 7 bearing frames 9 are secured. Short coupling beams 10 are removably attached to bearings 9 as by means of bolts 11. Brackets 12 secured to the under surfaces of the bearing frames 9

55 journal shafts 13 on which wheels 14 are keyed and which travel directly on the rails

5. Bearing brackets 15 secured upon the upper ends of the bearing frames 9 journal shafts 16 to which cranks 17 are rigidly connected and which journal shafts 18 extending from a table 19, of any desired construction and adapted for disposition with its upper surface in a plane passing intermediate the rolls A as seen in Figure 2.

Said rolling stock is adapted to be reciprocated relatively to the rolls A to move the table 19 toward and from the same and to this end, a link or pitman 20 is pivoted at 22 to the rear frame 6 and at 23 eccentrically to a rotatable disc 24 driven in any suitable manner as from a motor 25, to intermediate gearing within a casing 26 and a shaft 27.

Crank levers 28 are keyed to the shaft 16 and disposed on the opposite sides to the bearing frames 9 to cranks 17. At each end of each lever 28 a roller 29 is provided, being mounted and rotatable on horizontally disposed studs 30.

Four uprights or standards 31 are rigidly mounted upon the base 4 for cooperation with the levers 28. Ribs or flanges 32 extend outwardly from plates 31 and provide downwardly and rearwardly extending cam ways 34 open at both ends as at 35 and 36. One of the flanges 32 as at 37 forms a stop 80 or abutment for engagement with the rollers 29. Extending at an angle to the ribs or flanges 32 are ribs or flanges 38 on the standards 31 which provides cam ways 39 open at both ends. The innermost flanges 32 are 85 cut away at 40 to provide openings, which are normally closed by dogs 41, pivoted to the standards at 42 and adapted to remain in and seek the position shown in Figure 2. A stop 43 is provided on the standard 31 for 90 engagement by dogs 41 as they swing to open position, to prevent their passing the vertical. The outermost flanges 39 are cut away at their lower ends as at 44 and the openings provided are normally closed by 95 dogs 45, pivoted at 46 on the standards. Dogs 41 and 45 are normally maintained in and urged to the position shown in Figure 2 by counter weights 47 mounted on rods 48 extending from the dogs. Rods 48 at suitable locations have openings 49 therein to facilitate the attachment of a tripping hook or means to raise dogs 41 and 45. Handles 50 are provided for the manipulation of the dogs 41 and 45.

In operation, the motor 25 rotates the disc 24 in a clockwise direction and hence pitman

20 moves the rolling stock and the table 19 away from the rolls A with wheels 14 traveling upon the tracks 5 as will be understood. During such movement away from 5 the rolls A, the lowermost rollers 29, since the standards 31 are stationary, will travel in the camways 39, thus rocking levers 28, shafts 16 and cranks 17, shafts 18 and accordingly the table 19 so that the contents 10 of the table 19 may be removed in a higher or different plane. Further rotation of the disk 24 causes the other rollers 29 to move in the cam ways 34, resulting in lowering the shafts 18 and accordingly the table 19 15 and restoring the table and the apparatus as a whole to cooperative relation with the rolls A, that is, to the position of Figure 2. Levers 28 thus swing in the path of a complete circle from the axes of shafts 16. 20 When an unusually heavy load is being lowered and space is limited, the dogs 41 and 45 may be moved from over the openings 40 and 44 so that the rollers 29 may pass therethrough.

25 Since changes in the details may be resorted to, the same are reserved.

What is claimed is:—

1. A transfer apparatus consisting of a transfer member, truck frames, means to 30 connect said frames, wheels for said frames, means on each frame supporting said transfer member, and means to operate the last mentioned means to move the transfer member.

2. A transfer apparatus consisting of a transfer member, truck frames, bearing frames on said truck frames, wheels journaled on said truck frames, means mounted by said bearing frames to actuate the transfer member, and abutment means associated with the last mentioned means.

3. A transfer apparatus consisting of a transfer member, cranks journaled to said member, shafts for said crank, bearings for 45 said shafts, actuating levers for said shafts, cam means associated with said levers.

4. A transfer apparatus consisting of a transfer member, rolling stock, bearing frames on said rolling stock, shafts jour-

nalled on said bearing frames, cranks on 50 said shaft to which the transfer member is journaled, actuating levers on said shafts, and stationary cam means to cooperate with said actuating levers.

5. A transfer apparatus consisting of a transfer member, rolling stock, a pitman pivoted thereto, means to actuate the pitman, said rolling stock consisting of truck frames, means connecting the frames on said truck frames, axles journaled on said bearing frames, wheels on said axles, shafts, bearing members for said shaft on said bearing frames, cranks on said shafts journaled to said transfer member, levers on said shafts and stationary cam members associated with said levers to actuate the same.

6. In a device of the class described, means providing camways, an actuating means to enter said camways, said camways having openings leading thereto through which said actuating means passes, and means normally closing said openings.

7. In a device of the class described, means providing camways, an actuating means to enter said camways, said camways having 75 openings leading thereto through which said actuating means passes, and means normally closing said openings yieldable to expose the openings by engagement with said actuating means.

8. In a device of the class described having ribs providing a camway, said way being open at opposite ends, one of said ribs having an opening therethrough, second ribs providing a camway in communication with 85 said camway and disposed at an angle thereto, one of the second ribs having an opening, closures for said openings, operating means to pass through said camways, and means to permit movement of said 90 closures to uncover the openings.

In testimony whereof I affix my signature in presence of two witnesses.

JOHN J. HAZLEWOOD.

Witnesses.
